*Primary Examiner—Joel Sincavage**(74) Attorney, Agent, or Firm—Merchant & Gould P.C.*(57) **CLAIM**

The ornamental design for an intercom battery panel, as shown and described.

DESCRIPTION

FIG. 1 is a top perspective view of an exemplary battery having an exemplary battery panel in accordance with the present invention, where the battery panel of the present invention is not visible;

FIG. 2 is a bottom perspective view of the exemplary battery having the exemplary battery panel in accordance with the present invention;

FIG. 3 is a left side view of the exemplary battery of FIGS. 1 and 2;

FIG. 4 is a right side view of the exemplary battery of FIGS. 1 and 2;

FIG. 5 is a top view of the exemplary battery of FIGS. 1 and 2;

FIG. 6 is a view of the exemplary battery panel in accordance with the present invention;

FIG. 7 is a front view of the exemplary battery of FIGS. 1 and 2; and,

FIG. 8 is a rear view of the exemplary battery of FIGS. 1 and 2.

The broken lines throughout the drawing figures are included only for the purpose of illustrating an exemplary environment for the battery panel and form no part of the claimed design.
